CLAIM

The ornamental design for an electronic sensor and key
operated lock, as shown and described.

DESCRIPTION

FIG. 1 is a front, right perspective front view of an electronic
sensor and key operated lock showing the new design in
accordance with an embodiment;

FIG. 2 is a front view the electronic sensor and key operated
lock of FIG. 1;

FIG. 3 is a rear view of the electronic sensor and key
operated lock of FIG. 1;

FIG. 4 is a left, side view of the electronic sensor and key
operated lock of FIG. 1;

FIG. 5 is a right, side view of the electronic sensor and key
operated lock of FIG. 1;

FIG. 6 is top view of the electronic sensor and key operated
lock of FIG. 1; and,

FIG. 7 is a bottom view of the electronic sensor and key
operated lock of FIG. 1.

The broken lines represent the portions of the electronic
sensor and key operated lock that form no part of the
claimed design.

1 Claim, 6 Drawing Sheets
